(57) CLAIM

The ornamental design for a yoga ball plug, as shown and described.

DESCRIPTION

FIG. 1 is a perspective view of a yoga ball plug showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is an enlarged partial perspective view of the yoga ball plug, shown inserted into a yoga ball which forms no part of the claimed design; and

FIG. 9 is an enlarged partial perspective view of the yoga ball plug thereof, shown in an open position; and,

FIG. 10 is an enlarged partial perspective view of the yoga ball plug, shown removed from a yoga ball by users' hand, both of which form no part of the claimed design.

The broken lines depict environment and form no part of the claim.
